(57) **CLAIM**

The ornamental design for an aerating base, as shown.

DESCRIPTION

FIG. 1 is a top plan view of an aerating base in accordance with my invention;

FIG. 2 is a front elevational view thereof;

FIG. 3 is a perspective view thereof;

FIG. 4 is a bottom view thereof;

FIG. 5 is a rear elevational view thereof;

FIG. 6 is a right side elevational view thereof; and,

FIG. 7 is a left side elevational view thereof.

The structure indicated in the drawing figures by broken lines is not part of the design sought to be patented in this application.
